Primary Examiner—Celia A Murphy(74) *Attorney, Agent, or Firm*—Greer, Burns & Crain, Ltd.(57) **CLAIM**

The ornamental design for a footwear outsole, as shown and described.

DESCRIPTION

FIG. 1 is a perspective view of a footwear outsole showing my new design.

FIG. 2 is a right side elevational view thereof.

FIG. 3 is a left side elevational view thereof.

FIG. 4 is a front elevational view thereof.

FIG. 5 is a rear elevational view thereof.

FIG. 6 is a top plan view thereof; and,

FIG. 7 is a bottom plan view thereof.

The broken lines showing the footwear upper are for the purpose of illustrating environmental structure and form no part of the claimed design.

The broken-line shape in the arch region of FIGS. 1 & 7 represents an internal boundary of the design with neither the area within the lines, nor the lines themselves forming any part of the claim.
